YARN WINDING MACHINE

Robert E. Moser, Reading, Pa., assignor to Rose-dale Knitting Co., Inc., Reading, Pa., a corpora-tion of Pennsylvania

Application July 11, 1934, Serial No. 734,584

10 Claims. (Cl. 28—17)

This invention relates to yarn winding machines; and it has reference more particularly to machines for "back" winding defective ringless stocking blanks which for various reasons have been damaged in the factory, in order to recover for re-use, the different yarns from which the blanks were knit.

Stockings of the kind referred to are ordinarily knit from at least three different "body" yarns which are fed to the needles of the producing knitting machines in a predetermined repeating order or cycle to form successive courses of the stocking fabric.

In the main, my invention is directed toward making it possible to continuously recover and separately collect the several component yarns of defective ringless stocking blanks.

This desideratum I realize in practice through the provision of a reliable back winding machine which is simple in construction and capable of operation at high speeds, wherein the yarns are drawn from the stocking blanks by rotation of separate collecting spools maintained by their own weight in circumferential contact with driving rotor shafts so as to be capable of slipping when required, and wherein the spools are so arranged as to permit the yarns to pass and cross each other freely incident to raveling of the stocking fabrics with consequent minimization of entanglements and ruptures.

In connection with a back winding machine having the above attributes, it is a further aim of my invention to provide means whereby the yarn receiving spools for each stocking blank may be individually withdrawn from contact with the corresponding rotor shaft to permit interchange of spools, as well as means whereby the spools may be retracted as a group to facilitate yarn splicing in case breakages occur incident to the processes of back winding.

Still other objects and advantages of this invention will be manifest from the detailed description which follows of the attached drawings, wherein Fig. I is a broken out side elevation of a machine for back winding ringless hosiery conveniently embodying the present improvements.

Fig. II is an end elevation of the machine viewed from the right of Fig. I.

Fig. III is a plan view of the right hand end of the machine (as considered in Fig. I) drawn to a larger scale; and

Fig. IV is a fragmentary cross sectional view taken as indicated by the arrows IV—IV in Figs. I and III.

As herein delineated, my novel back winding machine comprises a pair of spaced end frames 1 and 2 which, at one side of the machine, are connected by a pair of vertically-spaced longitudinals 3 and 4 of angular cross section, and, at the opposite side of the machine, by similarly spaced longitudinals whereof the upper one 5 is cylindric as shown at the right hand of Fig. II, and the lower one 6 of angle section like the longitudinals 3 and 4.

The defective stocking blanks which are to be raveled are indicated at B, the same being hung side by side in horizontal rows from hooks 7 serially arranged along opposite faces of a longitudinal over-head beam 8. This beam 8 may be of wood, and, as shown, is supported by posts 9 upstanding centrally from the end frames 1 and 2 of the machine. The stocking blanks B are thus freely suspended for ready withdrawal of the yarns Y, Y' and Y² from which they were knit, under the pull of rotating collecting spools 10 in axial alignment along opposite sides of the machine, there being three such spools assigned to each stocking blank in this instance. As shown, the spools 10 are sustained for free rotation on the horizontal extremities 11 of arms 12 whereof the pivot sleeves 13 are confined between collars 14 on parallel fulcrum rods 15. These rods 15 extends the full length of the machine with their ends fixed in bosses 16 of the end frames 1 and 2. Normally, the arms 12 occupy the positions illustrated with the flanges of the spools 10 resting in circumferential contact with constantly rotating longitudinal rotor shafts 17 somewhat inward of and in a plane somewhat below the fulcrum rods 15, the spools being held centered between spacing collars 18 on said rotor shafts. Suitable journal bosses 19 on the end frames 1 and 2 afford the rotor shafts 17 appropriate bearing support. As a consequence of their pivotal connection with the rods 15 the spool sustaining arms 12 can be swung outward individually to the positions indicated in dot and dash lines in Fig. IV, in which positions they are held through engagement of projections 20 on their pivot sleeves 13 with longitudinal stop rods 21 extending along opposite sides of the machine in close proximity to the pivot rods 15. Obviously, when the arms 12 are individually swung to the dot and dash line position, their horizontal extremities 11 are readily accessible for application and removal of the spools 10.

To facilitate splicing of the yarns when ruptures occur, I have provided the means generally indicated at 22 whereby the group of arms 12

sustaining the yarn spools 10 for each stocking blank B may be concurrently swung back to inoperative position away from the rotor shafts 17. As shown, each such means 22 comprises a collar 23 which is rockable as well as slidable on the shaft 15, and which is provided with an upstanding grasp handle 24. Connected to the collar 23 is a shank 25 which extends horizontally beneath the three spool sustaining arms 12 of the corresponding group and which is formed with hook fingers 26 adapted, when the collar is shifted to the right, to engage the respective arms to simultaneously swing them to retracted position thereafter, by turning the handle 24 downward in Fig. IV. The end of the shank 25, it will be noted, is in each instance formed into a loop 26 which freely embraces the corresponding fulcrum rod 15 and assists in guiding and supporting the retracting means 22. Normally, the reTRACTING means 22 is held in the position shown in Fig. IV by contact of the projecting boss 27 of the collar 23 with the stop rod 21.

For the purpose of directing and tensioning the yarns Y, Y¹ and Y² en route from the stocking blanks B to the spools 10, and for evenly distributing the yarns on said spools, I have provided a traversing carriage 28 which comprises a pair of laterally-spaced parallel slide rods 29 which are guided for endwise movement in bosses 30 of the end frames 1 and 2 of the machine and which are joined at suitable intervals by cross heads 31. As shown, the cross heads 31 afford bosses 32 for the support of a pair of supplemental longitudinal rods 33, inward of the slide rods 29 and at a level somewhat below them. The rods 29 and 33, it will be noted from Figs. III and IV, are respectively fitted with pig-tail eyes 35 and 36, there being a pair of such eyes for each yarn withdrawn from the stocking blanks.

Reciprocatory movement is imparted to the traversing carriage 28 by a rotary cam 37 having a circumferential groove 38 engaged by a roller 39 on one of the cross heads 31 of said frame. The rotary cam 37 is secured to a shaft 50 journaled at one end in a boss 41 of the right-hand end frame 2 of the machine, and at the other end in a bearing 42 on a transverse girt 43 supported between the upper frame longitudinals 3 and 5.

The drive mechanism of the machine includes an electric motor 45 which is mounted on a plate 46 bridging the lower cross bar 47 of the end frame 2 (Figs. I and II) and the lower longitudinals 4 and 6. To the shaft of the motor 45 is secured a pair of pulleys 48 of small diameter. One of these pulleys 48, it will be observed from Fig. II, is connected by a belt 49 with a somewhat larger pulley 50 on one of the spool driving rotor shafts 17, from which latter motion is communicated at synchronous speed to the other spool driving rotor shaft 17 by a cross belt connection 51. The other pulley 48 on the shaft of the motor 45 is connected by a belt 52 with a relatively large pulley 53 on a transmission shaft 54 with journal support in a bracket 55 mounted on the plate 46 adjacent said motor. Alongside the pulley 53 on the transmission shaft 54 is a small pulley 56 which is coordinated by a belt 57 with a large pulley 58 on the cam shaft 40. The spool driving rotor shafts 17 are thus rotated at high speed, while the cam shaft 40 is rotated at a predetermined slower speed for actuation of the traversing carriage 28 to effect even distribution of the recovered yarns on the spools 10. The illustrated drive connections are of course to be considered as

typical of other forms of drive mechanisms which may be substituted if found more convenient or desirable in practice. The speed ratio between the cam shaft 40 and the spool driving rotor shafts 17 may moreover be changed as may be required by substitution of pulleys of different sizes.

From the foregoing it will be evident that I have provided a simple and reliable machine for back winding ringless hosiery, the spools 10 by virtue of resting by gravity on the rotor shafts having the capacity to slip so that one yarn may, in each instance, dwell until the selvages along opposite edges of the stocking blanks are cleared by the other two yarns, the aligned relation of the spools of each group permitting the yarns to cross and pass each other freely in their passage back and forth as they are raveled from the blank to the end that the possibility of entanglement and rupture is reduced to a minimum. Interchange of spools and yarn splicing or tying are easily and quickly effected by the facilities provided for the purpose. In back winding stockings made from very fine gauges, the yarns are passed through the eyes 35 on the slide rods 29 of the traversing frames only en route to the receiving spools 10, sufficient tension being thus imposed on them to insure back winding of said spools. In back winding stockings made from heavier gage yarns, the yarns are first passed through the eyes 36 of the supplemental rods 33 of the traversing carriage, as shown in dot-and-dash lines in Fig. IV, and then through the eyes 35 en route to the spools 10, being thereby caused to traverse a more devious path with incident imposition of additional tension so as to avoid looseness of the wrappings on the spools. The machine may obviously be made to any length according to the number of stocking blanks which are to be received at one time, and may be made either of single bank design or of double bank design as illustrated.

While I have described my improved winding machine as particularly adapted to back winding ringless hosiery, it may nevertheless be used for back winding ordinary stocking blanks made from single yarns instead of multiple yarns.

Having thus described my invention, I claim:

1. A back winding machine of the character described comprising a pair of end frames; longitudinal fulcrum rods extending along opposite sides of the machine with their ends secured in said end frames; synchronously-driven longitudinal rotor shafts inward of the fulcrum rods and journaled in said end frames; a series of arms pivoted on each of the fulcrum rods and individually sustaining, for free rotation, yarn receiving spools resting by gravity on the rotor shafts, said arms being individually swingable outward to a retracted position for convenience of interchange of spools; a longitudinal overhead beam supported by the end frames centrally over the machine and provided with means whereby rows of stocking blanks may be hung from its opposite sides; a longitudinally-traversing carriage with eyes for directing the yarns raveled from the stocking blanks and distributing them on the respective receiving spools along opposite sides of the machine; and means for reciprocating the traversing carriage.

2. A machine for back winding hosiery according to claim 1, wherein the traversing carriage comprises a pair of parallel rods slidably engaged in the end frames of the machine and connected at intervals by cross heads; and wherein the yarn guide eyes are carried by said rods.

3. A machine for back winding hosiery according to claim 1, wherein the traversing carriage comprises a pair of parallel rods slidably engaged in the end frames of the machine, cross heads 5 connecting the rods at intervals, and a pair of supplemental rods parallel to the slide rods and lying in a different plane with their ends secured in the cross heads; and wherein the slide and supplemental bars are provided with aligned eyes 10 to determine devious paths for the respective yarns en route from the stocking blanks to the spools.

4. A machine for backing winding hosiery in accordance with claim 1, wherein the reciprocating 15 means comprises a rotary cam with a circumferential groove engaged by a projection on one of the cross heads of the traversing carriage.

5. A machine for back winding ringless hosiery, comprising a pair of end frames; a longitudinal 20 fulcrum rod with its ends secured in said end frames; a longitudinal rotor shaft parallel with the fulcrum rod and journalled in the end frames; a longitudinal overhead beam supported by the end frames and provided with means 25 from which a row of stocking blanks may be hung; a group of axially-aligned spools assigned to each stocking blank, said spools being sustained for free rotation, resting by gravity on the rotor shaft aforesaid, by arms pivoted on the fulcrum 30 rod with capacity to be swung to a retracted position relative to the rotor shaft to facilitate interchange of the spools, and means whereby the sustaining arms of each spool group may be concurrently swung to retracted position for the 35 purpose of repairing broken yarn ends, each such means including an element capable of being slid on the corresponding fulcrum shaft to effect engagement of hooks thereon with the individual arms of the group, and of being thereafter turned on the fulcrum shaft to concurrently swing the arms as aforesaid.

6. A machine for back winding ringless hosiery in accordance with claim 5, wherein the swing 40 of the spool sustaining arms is limited by engagement of stop projections with a fixed longitudinal 45 rod supported by the end frames of the machine adjacent the fulcrum rod.

7. A winding machine of the character described comprising a horizontal spool-driving rotor with circumferential shoulders at intervals 50 along its length; and a plurality of gravity arms independently fulcrumed on an axis parallel with said rotor, said arms having horizontal pins at their outer ends for free endwise mounting and

withdrawal of winding spools with end flanges adapted to rest in peripheral frictional driving contact with the rotor and held against endwise displacement on the pins by engagement between adjacent circumferential shoulders on the rotor. 5

8. A machine for back-winding stockings and the like each knitted from a plurality of yarns, comprising a support for suspension of a number of stockings in a row; an aligned horizontal spool-driving rotor; a plurality of gravity arms 10 independently fulcrumed on an axis parallel with the rotor, said arms having horizontal mounting pins at their free ends for winding spools adapted to rest in frictional driving contact with the rotor; means for guiding the yarns from the several knitted fabrics and evenly distributing them 15 longitudinally of the individual spools; and means whereby the group of spool arms corresponding to each stocking can be swung past dead centers to a retracted inoperative position away 20 from the rotor independently of other such groups.

9. A winding machine of the character described comprising a horizontal spool-driving rotor with circumferential shoulders at intervals 25 along its length; a plurality of gravity arms independently fulcrumed for free up and down movement on an axis parallel to said rotor, said arms having horizontal mounting pins at their free ends for winding spools adapted to rest in 30 frictional driving contact with the rotor while held against endwise displacement on the pins between adjacent circumferential shoulders of the rotor; and means whereby groups of the spool arms may be swung past dead centers to an inoperative position away from the rotor independently of others. 35

10. A winding machine of the character described comprising a horizontal spool driving rotor with circumferential shoulders at intervals 40 along its length; and a plurality of gravity arms independently fulcrumed for free movement on an axis parallel to said rotor, said arms having horizontal mounting pins at their free ends for winding spools adapted to rest in frictional driving contact with the rotor and held against endwise displacement on the pins between adjacent circumferential shoulders on the rotor, and means pivoted on the fulcrum axis for the spool arms, whereby groups of said arms may be swung past 45 dead centers to inoperative positions away from the rotor independently of others. 50

ROBERT E. MOSER.
